UNITED STATES PATENT OFFICE.

HENRY B. RAMSEY, OF ROCKVILLE, INDIANA, ASSIGNOR TO HIMSELF
AND WELLS C. McCOOL, OF GUTHRIE CENTRE, IOWA.

IMPROVEMENT IN BED-BOTTOMS.

Specification forming part of Letters Patent No. 128,562, dated July 2, 1872.

Specification describing a new and Improved Bed-Bottom, invented by HENRY B. RAMSEY, of Rockville, in the county of Park and State of Indiana.

Figure 1 represents a vertical transverse section of my improved bed-bottom. Fig. 2 is a top view of the same.

Similar letters of reference indicate corresponding parts.

This invention relates to a new arrangement of the supporting-springs and cross-bars of a bed-bottom. It consists in the combination of flat springs fastened in the middle with the cross-bars and of cushions interposed between said springs and the cross-bars, and with rubber or leather plates placed upon the cross-bars and under the slats, as hereinafter more fully described.

A A, in the drawing, are the slats; B B, the cross-bars of the bed-bottom. The slats are, by screws or nails, firmly secured to the cross-bars. Strips a a, of leather or rubber, are interposed between the slats and cross-bars, as shown, to prevent wear and squeaking. To the middle of each cross-bar is secured,

at the under side, the middle of a supporting-spring, C, the ends of the spring being free and projecting downwardly, as shown in Fig. 1. The springs are to rest on the bedstead-rails, but are padded with rubber b, or leather, to be noiseless. In order to strengthen the springs and give a more firm support to the cross-bars cushions d d, of rubber, or spiral springs, may be interposed between B and C, as shown.

A bed-bottom thus made will be strong, elastic, noiseless, and self-balancing, the weight of a person on one side not interfering with the other side.

Having thus described my invention, I claim as new and desire to secure by Letters Patent—

The combination of the slats A, cross-bars B, springs C, strips a, pads b, and cushions d, as set forth.

HENRY B. RAMSEY.
